ROTARY HAMMER MILL

Theodore C. Alfred, Lancaster, Ohio

Application September 11, 1933, Serial No. 688,970
Renewed May 15, 1937

1 Claim. (Cl. 83—11)

This invention relates to improvements in rotary hammer mills of the character employed in grinding or reducing various products such as grain, stocks, seed, minerals and the like to a desired state of subdivision, the primary object of the invention being to provide a generally improved and more efficient machine for work of this character and one wherein high grinding capacity is provided with relatively low power consumption.

With these and other objects in view, which will appear as the description proceeds, the invention consists in the novel features of construction, combination of elements and arrangements of parts hereinafter fully described and pointed out in the appended claim.

In the accompanying drawings:

Fig. 1 is a side elevation of a rotary hammer mill formed in accordance with the present invention;

Fig. 2 is a front elevation thereof;

Fig. 3 is a vertical longitudinal sectional view taken through the mill;

Fig. 4 is a horizontal transverse sectional view on the line 4—4 of Fig. 3;

Fig. 5 is a perspective view of the mill with the casing plates at one side removed to disclose its interior structure;

Fig. 6 is a vertical transverse sectional view taken through the rotor;

Fig. 7 is a detailed view of the cam operated fastening means for retaining the cover of the mill casing in secured engagement with the stationary lower section of the casing;

Fig. 8 is a fragmentary sectional view of the rotor on the line 8—8 of Fig. 6;

Fig. 9 is a detail sectional view taken on the line 9—9 of Fig. 1.

Referring more particularly to the drawings, the numeral 1 designates the casing of the reducing mill. Preferably, this casing comprises a stationary lower section A and a removable cover or hood section B mounted on top of the lower section A when the mill is in operation. This casing may be constructed in any suitable manner from desired materials. In the present form of the invention, however, the lower section A comprises vertically disposed corner angles 1', horizontally extending pairs of top and bottom angles 2 and transversely extending top angles 3. These angles are suitably bolted or otherwise secured in rigid frame formation and also attached thereto are side and end plates 4 and 5 respectively. The casing may be mounted upon any suitable foundation either permanently or remov-

ably in order that during operation of the mill a stable working base, free from objectionable vibration, may be provided.

The cover or hood section B also provides corner angles 6 to which is secured in any suitable rigid manner a top plate 7, side plates 8, and a vertical end plate 9, the latter being provided, contiguous to its lower edge, with a transversely and horizontally extending exteriorly disposed angle member 10 arranged above and in registration with the top angle 3 of the base section A. The other side of the cover or hood B, opposed to the end plate 9, is substantially open, and carries an inclined feed trough 11 through or along which the materials to be reduced are fed into the rotor chamber C of the casing, and below the discharge end of the trough 11, the hood section carries a transversely and horizontally extending trap boxing 12 having the wall thereof which communicates with the chamber C slotted as at 13 in order to trap undesirable solids, such as miscellaneous pieces of metal, and prevent their coming into contact with the grinding elements of the mill. Preferably, studs 14 project from the ends of the boxing 12 and serve as fulcrums about which the hood section may turn in order to open or close the rotor chamber. Connected with the top wall 7 of the hood section is a slightly downwardly inclined baffle 15 which acts as a deflector in confining the material undergoing reduction to the limits of the chamber C.

An important feature of the present invention resides in the construction of the rotor D. This rotor comprises, in the preferred form of the invention, an axial support in the form of a shaft 16 which is suitably journaled for rotation in connection with bearings 17 mounted upon the upper surfaces of the top angles 2 of the base or lower section A. One end of this shaft carries a suitable form of belt wheel 18 by means of which power, obtained from any suitable form of prime mover, may be applied to the mill, while the opposite end of the shaft is connected with a suctional fan 20, the latter being disposed in a casing 21 arranged exteriorly and to one side of the mill casing, as shown more particularly in Fig. 2. The shaft 16, between the bearings 17, is threaded as at 22 for the reception of clamping nuts 23, which function to retain in assembled and clamped order a plurality of spaced flat bars, 50 comprising secondary hammers and designated generally by the numeral 24, in rotatable connection in unison with the shaft 16. If desired, the rotor shaft between its threaded portions 22 may be of polygonal design in transverse cross 55

section for reception within similarly formed openings provided in the intermediate portions of the bars 24 which comprise the secondary hammers.

5 It will be observed that these secondary hammers comprise a multiplicity of flat substantially rectangular bars of uniform length which have their intermediate portions connected for unitary rotation with the shaft or other form of axial support 16. Further, these bars are disposed in sets extending radially from the shaft 16 and are spaced substantially equidistantly at their outer ends to provide a plurality of relatively V-shaped pockets 25 therebetween, which pockets open to 10 the periphery of the rotor, as shown in Fig. 3. These bars may be of any suitable length and are compactly secured together in side by side relationship on the shaft for rotary movement in unison with the shaft, with the different sets of 15 bars spaced equidistantly around the orbit of travel of the rotor, and the advantages of this construction over the usual disc type of mounting, commonly found in grinding mills of this character, will be more fully described herein- 20 after.

25 Each set of bars at positions spaced from the axis 16 has the individual bars thereof provided with registering perforations for the reception of transversely extending cross pins 26 which may 30 be retained in connection with the bars by having their outer ends equipped with cotter keys 27. The pins 26 are employed to provide pivotal mountings for the reception of primary hammers 28. Each of these hammers comprises a 35 metallic casting or stamping of a thickness to be freely received within the spaces provided between adjoining bars of a set, and the opposite ends of these primary hammers are formed with perforations 29 for the reception of the cross pins 40 26 by means of which the said primary hammers are pivotally connected for independent swinging movement to the outer portions of the secondary hammers, so that while the primary hammers revolve with the secondary hammers and the axial 45 support 16, yet they are permitted to respond freely to centrifugal forces, set up by the rapid rotation of the rotor, usually a speed of 3300 R. P. M., to assume extended grinding positions wherein the outer ends of the primary hammers 50 project beyond the corresponding squared ends of the secondary hammers. These primary hammers may be of the type disclosed in my prior Patent No. 1,829,325, which have here been selected for illustration and include somewhat 55 tapering, stepped or shouldered ends 30, which have been found to be very effective in grinding operations of this character. Following a certain amount of use of the primary hammers with resulting wear, the positions thereof in connection with the secondary hammers or bars 24 may 60 be reversed to restore their normal operating efficiency.

65 One of the serious disadvantages in the ordinary reducing mill as heretofore constructed has been the lack of proper rotor weights, which have been seriously lacking in adequate fly wheel action. As a consequence, rotors of prior design with which I have experimented are not considered to possess a desired state of efficiency for 70 the reason that they require an excessive amount of power for a given output of ground material. In the design of the present rotor, however, I have discovered that by employing the grouped bars arranged in the compact fashion disclosed, the 75 weight of the rotor may be increased to augment

this fly wheel action and secure smoothness, lack of vibration, low power consumption and increased rotor diameter, all of which materially contribute to more efficient rotor operation. The increased diameter results in high peripheral 5 velocities and as a consequence still further improves the efficiency of the rotor. The use of the bars or arms 24 permits of the employment of a rotor having an effective diameter of approximately 28 inches, which may be operated 10 at a speed of 3300 R. P. M. with the use of a suitable prime mover. These proportions add greatly to the efficiency of the mill, as a much harder blow is struck on the material being reduced than when a rotor of smaller diameter is used and, 15 moreover, there is no loss in the actual number of blows struck per minute. This is a marked contrast with the usual type of rotor employing spacing discs for the centrifugal hammers. Such discs do not in the ordinary mill function to 20 strike blows upon the material being reduced, as do the secondary hammers or bars 24 here disclosed. In the present rotor, with the power input remaining constant, the arms or bars provide increased diameter over the ordinary disc 25 type rotor, adequate weight for the desired fly wheel action, grinding or reducing operation from the bars or secondary hammers, and augmented peripheral velocity of the outer or primary hammers carried thereby.

30

In common with prior hammer mills of this general character, I employ a semicircular perforated plate or screen 31 beneath the lower half of the rotor. In contrast, however, with previous screens, the screen 31 is set so that it is disposed 35 slightly eccentrically of the axis of the rotor, or conversely the axis of the rotor is eccentric to that of the screen. This eccentricity is such that the screen is spaced roughly at approximately $\frac{3}{4}$ of an inch from the outer orbit of the rotor at 40 the front of the mill, tapering to approximately $\frac{1}{2}$ of an inch at the bottom and to about $\frac{1}{4}$ of an inch at the rear. These figures are of course approximate and are subject to variation if found desirable. By this eccentricity of the rotor with 45 respect to the screen, I have been able to secure a more efficient grinding or reducing operation and have increased materially the capacity of the mill over the usual construction wherein the screen exactly conforms to the orbit of the rotor. 50 In the operation of a screen of this character, it is important that it should shed finely divided materials through the openings or perforations thereof rapidly so that the ground materials may pass freely therethrough. To this end I mount 55 the screen 31 in arcuate guides 32 in which the screen is free to move until one end thereof contacts with a stationary abutment 33 disposed adjacent to the trap 12. The opposite edge of the screen is then so disposed as to engage with the 6 lower portion of the cover or hood B when the latter is closed, so that upon the final clamping of the hood in its closed position, the screen will be placed under compression, the purpose of this being to maintain the screen in what may be 6 termed a "tuned" state when the mill is in operation so that the minute and rapid vibration thereof will serve to cause a rapid and effective passage of the finely ground materials through the perforations thereof.

To obtain the locking of the hood in its closed position and the screen under compression as described, the angle 3 of the base section is formed intermediately of its length with an opening for the reception of a swinging eye bolt 34. This eye 7

bolt, as shown in Fig. 7, is receivable within an open ended slot 35 provided in the angle member 10 of the hood section. Also formed with the bolt 34 is a stationary cam enlargement 36, which 5 cooperates with a movable cam 37 which is turnable about the axis of the bolt shank. The outer or upper end of the bolt may be provided with a nut 38 and a spring may be positioned between the nut 38 and the movable cam 37. The cam is provided with a lateral handle extension 40, and also a stop lug 41. When this fastening is positioned in hood securing relationship, the handle 40 is actuated to rotate the movable cam until the stop lug 41 contacts with the end plate 15 9. Due to the inclined plane action, downward pressure will then be imparted to the hood causing it to exert a considerable force on one of the upper horizontal edges of the screen to maintain the latter under compression and at the same 20 time to securely retain the hood section in closed operative relationship with the stationary lower section of the mill casing.

The ground material drops into a trough 42 formed within the confines of the base section of the mill and is discharged therefrom by way of a conduit 43 by the suction created through the operation of the fan or blower 20. The divided material may then be delivered from the fan to a suitable form of separator (not shown) or other 30 position of material deposit.

As set forth in my prior Patent No. 1,829,325, there is a decided tendency for ground material to clog the openings provided in the upper portion of the screen at the front of the mill. Due 35 to the curvature of the screen, the openings which extend therethrough at this portion thereof are substantially horizontal, or more nearly the horizontal than the vertical and, therefore, material which collects in these openings does not so 40 readily respond to gravity and as a consequence the screen clogs in this area. To take care of this condition, the front of the mill in the present invention is provided with a slot 44 open to the atmosphere and formed between the adjoining 45 edges of the laterally offset walls of one of the end plates 5 and the vertical end plate 9, and through which slot air from the atmosphere may be drawn. By the operation of the mill and the suction developed by the operation of the fan 50 20, air drawn into the mill through the slot 44 travels at a high velocity past the forward upper edge area of the screen, creating suction forces by which materials which normally clog that particular part of the screen are positively removed from obstructing positions and delivered to the trough 42 for subsequent discharge from the mill.

Attention is directed to the cross sectional configuration of the hood section as more particularly disclosed in Fig. 3. The angles of the top plate 7, the vertical end plate 9 and the deflector plate 15 are such that the material in this portion of the rotor chamber is kept moving back and forth on the rotor between the ends of the 5 hammers and the angular walls of the hood. For example, theoretically, material falling on a set of hammers when the latter are in a horizontal position, will be thrown against the deflector baffle 15 in the hood above the feed table. While 10 this material will not lose all of its rotary and forward motion, nevertheless, it will be deflected back onto the hammers to then strike the slanting top wall 7 of the hood, thence again back upon the hammers and into contact with the forward wall 9, being constantly reduced by this

agitation and contact with stationary or moving surfaces, so that the material will be divided to a desired state by the time it reaches the screen area. Preferably, the inner surfaces of the walls 7 and 9 are provided with a screen lining as indicated at 45. This lining not only changes the direction of the material contact therewith from a deflecting standpoint but it also has a certain cutting effect on the material at the edges of its openings, and, in addition, the lining serves to 10 slow up or retard the forward motion of the feed or other material undergoing reduction.

It will be observed that the feed chute or trough 11 enters the rotor chamber at a point just above the plane of the axial center of the rotor. This is 15 a considerably lower point than has been customary in previous hammer mill designs, and a decided advantage is obtained by this lowering of the feed chute, in that it provides for a more extended contact between the primary and secondary 20 hammers in the upper portion of the rotor chamber, or in the hood area, with consequent greater reduction of the material before the screen area is reached. It is in this portion of the rotor chamber that the arms or secondary 25 hammers function as reducing agents since the large material readily drops into the V-shaped spaces formed between the adjoining sets of bars or arms comprising the secondary hammers, but this is accomplished with but a negligible consumption of power. Where power is largely expended is in passing the primary hammers through the bed of finely ground material retained on the upper surfaces of the screen, but since this bed rarely exceeds a depth in excess 30 of $\frac{3}{4}$ of an inch, it will be seen that the secondary 35 hammers or bars during their travel through the lower half of the rotor chamber will be out of contact with the material being acted upon and thence will not consume any appreciable power in 40 this portion of the mill operation.

Any desired grouping of the primary hammers on the several sets of bars may be provided. It is important however that the primary hammers should be placed in such sequence between said 45 bars that the rotor will be substantially statically and dynamically balanced. Preferably, each set of bars carries eight hammers, four at each end, as shown in Fig. 4. By laterally offsetting the 50 hammers of each set with respect to those of adjoining sets, the material undergoing reduction may be moved back and forth longitudinally of the rotor chamber and yet prevented from accumulating at the ends of said chamber.

The trap boxing 12 is arranged substantially 55 in registration with the horizontal plane of the axis of rotation of the rotor. Its forward wall is provided with a slot 13 disposed in communication with the rotor chamber C so that as the rotor revolves, any foreign particles, such as bits 60 of metal or the like will, by centrifugal force, be advanced into the boxing where such foreign particles will be imbedded in the reduced material which collects in this boxing during the 65 operation of the mill. Preferably, the boxing is provided with a removable rear wall 47, which may be instantly removed by the mere loosening of the wing nut 48 shown in Fig. 4, so that in the event of fire in the boxing, the same may be readily extinguished by the removal of the 70 rear wall 47. The latter is ordinarily used for removing accumulated particles of matter from the boxing.

The eccentricity of the screen mounting is such that in one of the commercial forms of my im- 75

proved hammer mill, the clearance between the ends of the hammer and the screen proper at the forward upper end of the screen is approximately three-fourths of an inch. This eccentricity provides a clearance of approximately one-half of an inch at the bottom of the screen and approximately one-fourth of an inch at the upper rear end of the screen. While this degree of eccentricity may be varied, the eccentricity thus afforded provides more freedom between the ends of the hammers and the screen in the three-quarter inch space and allows further reduction without as much drag or power consumption. In other words, the tapered circle admits larger portions at one end than would a concentric circle only one-half an inch away from the ends of the hammers, doing away with shock loss at the point of entry over the screen because of the greater space provided. At the other end, the reverse is true. However, by this time the materials are finely divided and by operating the hammers closer to the screen, a greater output is obtained.

Heretofore hammer mills of this character have been formed to include heavy cast metal casings which have been considered necessary in order to minimize vibration in the operation of the rotor at high speeds and to preserve bearing alignments. In the design of the present mill, however, I use a separate angle construction or sub-frame composed of structural metallic members to which are bolted or otherwise secured the wall plates. Normally, it would be thought that this construction would be ample to avoid deflection but if unprotected such deflection would exist. While almost no force would be great enough in the operation of the mill, even up to 75 H. P. application, to distort this frame structure permanently or really damage it in any way,

yet there is an initial deflection before the full resistance of the steel is obtained, which would be very detrimental and cause trouble with shafts and bearings.

To overcome this, I use the braces 49 which are connected as shown in Figs. 1 and 2 with the upper and lower sets of angle members 2. In order to make these braces effective and produce a rigid solid frame construction, the lower frame is assembled including the members 1', 2, 3, 4 10 and 5, and an expander (not shown) is inserted to spread apart the upper and lower angles until there is produced a decided buckle in the side sheets. The braces 49 are then cut to such length that when they are inserted and secured, this 15 deflection of the frame will be maintained following the removal of the expanding means. In this way, I overcome entirely any tendency of flexure in the frame. By the employment of these pressure braces, the middle is relieved entirely from this initial flexure which would otherwise be present and also I am enabled to avoid the use of inordinately heavy steel members.

What is claimed is:

In a rotary hammer mill, a casing comprising 25 a structural steel frame of substantial cubical form, including rigidly united upper and lower sets of horizontally disposed rails and vertically extending post rails, sheet metal plates secured to the sides and ends of said rails and defining 30 a rotor chamber, a rotor arranged in said chamber and including a shaft mounted for rotation in bearings carried by the upper set of horizontally disposed rails, and brace members under compression uniting the upper and lower sets of 35 horizontally disposed rails and arranged to deflect said frame structure and hold it under tension.

THEODORE C. ALFRED.
